UNITED STATES PATENT OFFICE.

CHARLES C. HANSEN, OF NEW YORK, N. Y., ASSIGNOR TO THERMAL APPLIANCE COMPANY, INC., OF NEW YORK, N. Y., A CORPORATION OF NEW YORK.

WATER-HEATER.

1,311,391.

Application filed November 27, 1916. Serial No. 133,581.

Specification of Letters Patent. Patented July 29, 1919.

To all whom it may concern:

Be it known that I, CHARLES C. HANSEN, a citizen of the United States, and a resident of New York, borough of Manhattan, county 5 of New York, and State of New York, have invented certain new and useful Improvements in Water-Heaters, of which the following is a specification.

My invention relates to water heaters, particularly to that type in which water circulatory pipes extend through steam pipes to be heated by the flow of steam and in which expansion of piping is depended upon to operate a valve for controlling the inlet of 15 steam.

Prior devices of this class are more or less complicated and expensive of construction, and the object of my invention is to simplify the construction and to produce a very efficient heater which can be inexpensively manufactured.

My improved construction and its advantages will be apparent from the following specification and the accompanying drawings, in which drawings—

Figure 1 is a top view,

Fig. 2 is a sectional view on plane 2—2;

Fig. 1,

Fig. 3 is a sectional view on plane 3—3,

Fig. 2,

Fig. 4 is a sectional view on plane 4—4;

Fig. 3, and

Fig. 5 is a sectional view at the lower end showing a modified arrangement.

Referring to the drawings, A designates as a whole the upper header structure and B the lower header structure. The upper header structure is in the form of a rectangular casting 10 having the bottom wall 11, the intermediate horizontal partition 12, and the centrally located vertical partition 13, together with a removable cover 14. The horizontal and vertical partitions are preferably cast integral with the body 10 and divide the body into the two upper compartments 15 and 16 and the two lower compartments 17 and 18. At one end the compartment 16 has the inlet 19 for cold water and at the opposite end the compartment 15 has the hot water outlet 20. The compartment 18 has the steam inlet 21 and the compartment 17 has the steam exhaust outlet 22.

The lower header structure B is in the form of a rectangular casting 23 having the top wall 24, the intermediate wall or par-

tition 25, and the detachable cover 26 which forms the lower wall, the casting 23 having the flange 27 to which the cover is secured by bolts 28. The walls form the upper and lower chambers 29 and 30 respectively. Extending between the walls 11 and 24 of the upper and lower header structures are the two sets of steam pipes 31 and 32, the pipes being rigidly secured at their ends to the walls and the pipes 31 connecting compartment 17 with the compartment 29 and the pipes 32 connecting compartment 18 with compartment 29, steam flowing from the inlet 21 to compartment 18, then in parallel through the pipes 32, and through the compartment 29 through pipes 31 into compartment 17 from where it exhausts through outlet 22. Anchored at their lower ends to the wall 25 of the lower header are two sets of steam pipes 33 and 34, the upper ends of pipes 33 being slidable in stuffing boxes 35 and these pipes connecting compartment 15 of the upper header with compartment 30 of the lower header. In a similar manner the pipes 34 extend through stuffing boxes 36 and connect compartment 16 with compartment 30, the bushings being supported in the horizontal partition 12. Cold water thus enters compartment 16 through inlet 19 and flows through pipes 34 into compartment 30, and from there through pipes 33 into compartment 15, the heated water leaving the outlet 20, it being understood that the water on its circulation through the water pipes which extend through the steam pipes is heated by the steam.

The inlet of steam is controlled by a valve 37 and preferably the operation of the valve to control the flow is automatically accomplished by the force of expansion and contraction of one of the water pipes. As shown, the pipe 33^a has been selected for such control, the upper end of this pipe being connected by a coupling 38 with a stem 39 which passes through a stuffing box 40 on the cover 14. The upper end of the stem carries a pivot fitting 41 for the inner end of lever 42, this lever being pivoted or fulcrumed at an intermediate point on the bolt or pin 43 held in the pivot post 44. At its outer end the lever is pivoted to the fitting 45 which is adjustably secured at the upper end of the valve stem 46 of the valve 37. To support the bearing post 44 a vertical rib 47 is provided on the cover 14 and pref-

erably cast integral therewith, the legs 48 and 49 of the bifurcated lower end of the post receiving the rib between them and having preferably jointed engagement therewith, as indicated at 50. The post is thus shiftable on the rib to adjust the fulcrum pin 43, the lever 42 having the longitudinal slot 51 for the fulcrum pin 43. After adjustment of the post it can be 10 rigidly secured by tightening of the bolt 52 to clamp the rib between the legs 48 and 49. The adjustment depends upon the degree of water heating desired, steam and water flowing through the respective pipes and 15 the steam heating the water, and as the controlling pipe 33^a expands under heat the valve will be gradually closed and when the water is at the desired temperature the valve will be fully closed. As soon as the 20 water cools the pipe 33^a will contract and will re-open the valve for the further flow of steam, the regulation of the steam flow being thus automatically accomplished and the temperature of the water maintained at 25 the desired point. Instead of having the water flow in the same direction as the steam, it is evident that the water inlet and outlets could be interchanged and water caused to flow in a direction opposite to 30 that of the steam.

It will be noted that instead of using the flat cover on the upper header a curved or domed cover is used. This will enable shortening of the water compartments with- 35 out decreasing the volume or area thereof and the header can therefore be reduced in size and weight. By casting directly on the cover 13 the support for the lever fulcrum post, the construction is very much simpli- 40 fied and the cost reduced.

It may sometimes be desirable to filter the water. In my construction this can be very readily accomplished. Referring to Fig. 5, a tablet 53 of filter material is inter- 45 posed in the flow of the water from the pipes 34 to 33, and to accommodate a filtering tablet of sufficient filtering area an extension 54 is provided to be inserted between the flange 27 and the cover 26, the extension 50 having the flanges 55 and 56 for securing it to the flange 27 and to the cover respectively. Thus when it is desired to filter the water the cover 26 is removed and the extension 54 with the filter block therein in- 55 troduced. To help support the filter block centrally between the two sets of water pipes the cover may have the longitudinal groove 57.

My improved heater requires very few parts, and such parts are of the simplest 60 shape and preferably in the form of castings, and very little finish work is required. The same construction can be utilized in different capacity heaters by making the headers of corresponding length and connecting them with the necessary number of 65 pipes. The assembly of the parts requires very little labor as when the covers are off the pipe connections and bushings are very readily accessible.

I do not, of course, desire to be limited to the exact details of construction and arrangement shown and described as modifications are no doubt possible which would still come within the scope of the invention.

I claim as follows:

1. In a water heater of the class de- 80 scribed the combination of header structure having water and steam compartments, steam pipes connecting said steam compartments, water pipes connecting said water compartments and passing through said steam pipes, a valve for controlling the steam flow, a stuffing box on the top of said header, an expandable member anchored at 85 one end and extending through one of said steam pipes and through said stuffing box, a lever pivoted at one end to said expandable member and at its other end to the stem of 90 said valve, a transversely extending rib integral with said header top, said rib having guide grooves in its opposite sides, a bifurcated fulcrum post receiving said rib and having tongues in its opposite sides for en- 95 gaging in the rib grooves, a bolt extending through said post for drawing the bifurcated ends thereof together to clamp said rib, said post at its upper end having pivotal connection with said lever.

2. In a water heater, the combination of 100 an upper header structure and a lower header structure, said upper header structure being sub-divided into two water compartments, two sets of water pipes connecting the water compartments with said lower header structure, a cover for said lower header structure, and a filter plate clamped in vertical position in said lower header structure between said cover and the base of said structure to be interposed in the 105 flow of water through said header structure from one set of pipes to the other.

In witness whereof I hereunto subscribe my name this 23rd day of November, A. D. 1916.

CHARLES C. HANSEN.
